Primary Examiner — Marie D. Fast Horse

(74) **Attorney, Agent, or Firm:** Suzannah K. Sundby,
Esq.; Canady + Lortz LLP

(57) **CLAIM**

The ornamental design for an electronics module, as shown and described.

DESCRIPTION

FIG. 1 is a top perspective view of an electronics module showing my new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The features shown in broken line in the Figures show portions of the electronics module that form no part of the claimed design.

1 Claim, 8 Drawing Sheets
